George P. Schrader, Springfield, Oreg., assignor of a fractional part interest to Charles I. Schrader, Springfield, Oreg.

Filed Nov. 17, 1975, Ser. No. 632,297

Term of patent 14 years

Int. Cl. D7—02; D23—02

U.S. Cl. D23—72

FIG. 1 is a perspective view of a combined heating and cooking stove embodying my new design;

FIG. 2 is a front elevational view thereof;

FIG. 3 is a fragmentary top plan view thereof;

FIG. 4 is a side elevational view taken from the right of FIG. 1, the side opposite being a mirror image thereof with the exception of the position of the handles and hinges;

FIG. 5 is a rear elevational view thereof.

I claim:

The ornamental design for a combined heating and cooking stove, as shown.
